UNITED STATES PATENT OFFICE.

THOMAS HENRY SMITH, OF JAMESTOWN, NEW YORK.

UNION SUIT.

Application filed March 23, 1921. Serial No. 454,639.

To all whom it may concern:

Be it known that I, THOMAS HENRY SMITH, a citizen of the United States, residing at the city of Jamestown, in the county of Chautauqua and State of New York, have invented certain new and useful Improvements in Union Suits, of which the following, taken in connection with the accompanying drawings, is a specification.

10 The invention relates to undergarments, with the idea of doing away with all or nearly all buttons so that there are none to be smashed in the laundry, yet providing means whereby the interlapping parts may 15 be quickly and easily opened or retained in the closed position.

Accordingly, the object of the improvement is to provide means for holding the lapping or interlapping parts of the undergarment with adaptation to the figure of the individual and thereby produce a buttonless or nearly buttonless undergarment; and the invention consists in the novel features and combinations hereinafter set forth and 25 claimed.

In the drawings, Figure 1 is a front elevation of the trunk portion of a man showing the front lap of a union suit and the manner of closing the same. Fig. 2 is a rear elevation of a man with the union suit thereon showing the manner of closing and holding the back flaps; and Fig. 3 is an enlarged view of said back flap portion of the undergarment showing the preferred construction 35 and arrangement of the parts with the draw cords in position, the garment being broken away to reveal the attachment and arrangement of the cord for the under flap, the manner of opening said flaps being shown in 40 dotted outline. Fig. 4 is a crosswise sectional view at lines 4—4 in Fig. 3 showing the preferred construction of the cloth guideways for the draw cords. Fig. 5 is a modification showing one of the flaps or lapping parts attached by a draw cord and a button attached to said lapping part. Fig. 45 50 55 60 65 70 75 80 85 90 95 100 105 110

Like characters of reference refer to corresponding parts in the several views.

The numeral 10 designates the undergarment which has the front interlapping flaps 55 or portions 11 and 12 and the back flaps or interlapping portions 13 and 14, the remain-

der of the garment being made in the usual manner to fit the figure of the individual.

In order to hold the interlapping parts 11, 12, 13 and 14 in position, yet permit the 60 free and easy movement of the individual, and also to provide for the quick opening and closing attachment of said interlapping portions, preferably knit or woven soft tubular cords 15 and 16 are attached to the edges, 65 one to each interlapping portion, preferably by sewing the same upon the interlapping part near its edge portion as shown at 17, the cord 15 being attached to the outer lap, and the cord 16 to the under or inner lap. 70

Each of the cords 15 and 16 are preferably attached by looping the same in their central portion and attaching the looped or return bend end as shown at 17, thence carrying said cords horizontally or at right angles 75 to the edge of the lapping portion to which it is attached, and inserting through tubular cloth guideways 18, one for each of the cords, which guideway 18 is preferably made by attaching a piece of cloth 19 to the garment 80 10 a spaced distance from the edge of the lapping part by sewing said piece of cloth 19 along each side of the strands of cord 15 or 16 so as to fit closely upon the same and provide a frictional draw for said cords. 85

Said cords are preferably knotted or otherwise attached to one another as shown at 20 so that after insertion through the close fitting cloth guideways 18 and attachment to one another, the parts of the cords 90 95 100 105 110

15 or 16 are fixed in their attachment to the undergarment so that they cannot get out of position in respect to the same, but are always ready for immediate use. The cord 16 attached to the under or inner flap or lapping portion 14 is brought out through the garment 10, preferably through a reinforced eyelet 27 which has been properly overcast so as to make a durable construction permitting the draw of the two 100 cords through the same. Said cords may be drawn through the one hole or through separate holes as desired, the cord 16 thence passing out through the tubular guideways 18 and attached to one another at 20. The one eyelet 27, however, reduces the amount of work and serves the purpose equally well.

It is apparent that the front flaps 11 and 12 or the rear flaps 13 and 14 may be attached over one another in substantially the same manner and that when said soft tubu-

lar cords 15 and 16 are extended out through the frictional tubular cloth guideways 18, they hold with peculiar tenacity, yet enable the wearer to assume any position and allow 5 also for drawing or withdrawing the cords so that an easy, comfortable fit is acquired by the wearer of the same.

In order to enter or put on the garment, the cords 15 and 16 for the front flaps 11 and 10 12 should be of sufficient length to permit the free opening of the neck portion so that the garment may be drawn up over the body and the arms entered into the sleeve portions. The cords 15 and 16 for the back 15 flaps 13 and 14 may be looped into one another across the abdomen as shown in Fig. 1 by simply inserting the knot 20 through the looped end of the opposite cord, though this is not usually found necessary in order 20 to hold the parts firmly in position, since if the cloth pieces 19 are sufficiently long to provide guideways 18 of fair length, the frictional holding of said guideways upon the cords holds the garment firmly in shape. 25 In case of an abnormal strain for any reason, said cords and guideways permit the garment to give somewhat, thereby overcoming such strains much more easily and comfortably than in the case of buttons which 30 would be torn off the garment and have to be replaced, the wearer waiting for a convenient opportunity to have replacement of the same.

In the modification shown in Fig. 5, a 35 button 21 is provided on the edge of the lapping portion, and the end 22 of the cord 23 is looped and fastened preferably by a thread around the same to thereby provide an eyelet or button-hole 22 in the end of the 40 looped cord to fasten over said button 21. This modification depends upon the cloth guideways 18 formed by the attached cloth 19 upon the garment 10 to hold the laps or flaps the same as in the preferred form of 45 attachment as shown at 17.

In the modification shown in Fig. 6, a single cord 24 attached to the edge of the

lapping portion extends through a single guideway 25 and has a knot 26 near its end to prevent slipping back through the guideway 25. The single cord attains a fair purpose where no great strains come upon the interlapping parts, but it is usually preferred and but little more work to provide the two slidably mounted draw cords with 55 their double guideway and holding power.

What is claimed is:

1. In combination with a garment having overlapping parts with free outer sides, a cord for each part doubled between its ends to form parallel portions that are affixed at the doubled end to the part, relatively short fabric members affixed to the garment adjacent to the respective free sides of the overlapping parts to provide a pair of parallel spaced guides which frictionally receive the respective parallel portions of the cords, the free ends of the respective cords being tied together at points beyond the fabric members so as to engage the outer ends thereof at points between the parallel guides to thereby restrict the extent of inward movement of the cords relative to the guides. 65

2. In a garment having an overlapping part with a free outer side, a draw string for each part attached at one end to the outer side thereof, said garment having a pair of closely spaced parts for the overlapping part which spaced parts are formed to receive portions of the string, the string being 70 threaded in and out of the spaced parts so that portions of the string engage both the inner and outer faces of the garment whereby the string is frictionally held by each of 75 said spaced parts and also by the inner and outer faces of the garment adjacent to the spaced parts. 80

In testimony whereof I have affixed my signature in the presence of two witnesses.

THOMAS HENRY SMITH.
